Gabriel Samard,
INVENTOR

BY Victor J. Evans

ATTORNEY

UNITED STATES PATENT OFFICE

GABRIEL SAMARD, OF CANBY, OREGON

PICTURE-FRAME HANGER

Application filed March 20, 1930. Serial No. 437,549.

The object of this invention is the provision of simple means for adjustably securing a picture wire or cord upon a picture frame which will obviate the necessity of twisting the wire against a screw eye or the like and depending the adjustment of the picture by such twisting, and which, in addition to providing a means for securely fastening the wire to the frame permits of the adjustment of the frame on the wire, so that the picture can be hung at desired elevations and effectively retained in proper position.

To the attainment of the foregoing the invention consists in the improvement herein-after described and definitely claimed.

In the drawings:

Figure 1 is a front elevation of a picture suspended in accordance with this invention.

Figure 2 is a rear elevation thereof.

Figure 3 is a rear elevation showing a picture frame provided with two of the cord or wire clamps.

Figure 4 is a sectional view approximately on the line 4—4 of Figure 2.

Figure 5 is a perspective view of the base member or clamp.

Figure 6 is a similar view of the spring influenced pivoted clamp member or dog.

As disclosed by Figure 2 of the drawings one end of a wire or picture cord 1 may be attached to the back of a picture frame 2 by connecting the said wire to the usual screw eye. The wire is directed around the looped portion of a hanger 3 which is secured to the wall of a room. The second end of the wire 1 is secured on the picture frame by my improvement.

Before entering a detailed description of the improvement it is to be stated that instead of one, two of such clamps may be fixed on the rear face of the picture frame, as disclosed by Figure 3 of the drawings in which instance two supporting wires are employed. Each of the clamps comprises a base plate 4 formed, adjacent its ends with openings through which pass securing elements that enter the rear of the picture frame. Each base plate, adjacent to what I will term its outer end is provided with an outstanding right angle lip 5 and this lip has a central

opening 6 therethrough for the passage of the wire 1. The base plate is provided with longitudinally extending spaced side flanges 7 disposed a suitable distance inward of its edges, and the plate between the lip and the side flanges is open, as indicated by the numeral 8.

Pivottally secured, as at 9, between the side flanges 7 of the base plate 4 there are the sides 10 of the body plate 11 of the jaw carrying member or dog. The jaw of the dog is formed by bending one end of the plate 11 at an acute angle, as indicated by the numeral 12, and this angle end is formed with a central notch 13 which is designed to be arranged opposite the opening 6 in the lip 5. The notch 13 is substantially V-shaped and the outer edge of the dog end of the swingable member of the clamp is provided with other V-shaped openings 14 that afford therebetween points 15. A spring 16 is wound around the pivot 9 and has one end contacting with the plate 11 and its other end contacting with the frame 2, the said end of the spring being received in the opening 6.

By reference to Figure 4 of the drawings it will be noted that the angle or jaw end of the dog element of the clamp is disposed a suitable distance inward of the lip 5 of the base plate 4, and likewise that the depth of the notch 13 is such that the same will cause the portion of the wire received through the opening 6 and through the notch 13 to assume an angle, and further that because of the angle walls provided by the notch 13 the wire will be frictionally engaged by such walls. In addition to this it will be noted that the points 15 will, through the medium of the spring 16, enter, to a determined extent the wooden frame 2, so that the dog is effectively held from accidental movement and the wire that passes through the improvement is tightly held between the lip and jaw and likewise the angle or offset portion thereof engaged in the notch 13 is forced against the inner face of the frame 2.

It is believed the foregoing description when read in connection with the accompanying drawings will fully set forth the construction and advantages of the improve-

ment to those skilled in the art to which such invention relates so that further description will not be required.

Having described the invention, I claim:

- 5 1. A device for adjustably clamping a supporting wire or cord on a picture frame including a base plate, a right angle lip on the base plate having an opening therethrough for the passage of the wire, side flanges on the plate, a dog having side flanges which are pivoted in the side flanges of the plate and which has a notched end that is bent at an angle to the body of the dog and which is arranged opposite but spaced from the lip 10 of the plate, a spring for swinging the angle end of the dog toward the plate to cause the notch in said end to be arranged out of a line with the opening in the lip.
- 15 2. A clamp for adjustably securing a picture wire on a picture frame, comprising a base plate, said plate having an outstanding right angular lip provided with an aperture for the passage of the wire therethrough and having longitudinally extending side flanges 20 and a portion between the plate and the side flanges being cut away, a clamping dog having side flanges which are pivotally secured between the side flanges of the plate, said dog also having an end that is bent at an angle to 25 the body of the dog and is formed with a plurality of U-shaped notches, the said end being arranged opposite but out of contact with the lip of the plate, one of the notches 30 in the bent end of the dog designed to receive 35 the wire therein for binding engagement therewith, for holding the wire adjusted and the remaining teeth of the dog designed to bite into the picture frame.

In testimony whereof I affix my signature.

40 GABRIEL SAMARD.
